UNITED STATES PATENT OFFICE

141,276

DESIGN FOR A CONDIMENTS SERVER

Herbert W. Krupp, Racine, Wis.

Application January 10, 1945, Serial No. 117,367

Term of patent 7 years

(Cl. D44—7)

To all whom it may concern:

Be it known that I, Herbert W. Krupp, a citizen of the United States, residing at Racine, in the county of Racine and State of Wisconsin, have invented a new, original, and ornamental Design for a Condiment Server, of which the following is a specification, reference being had to the accompanying drawing, forming a part thereof.

I claim:

The ornamental design for a condiment server, as shown.

HERBERT W. KRUPP.
